SWITCH FOR TABLE CIGARETTE LIGHTER

William Retzler, Wickham, England, assignor to Colibri
Lighters Limited, London, England

Filed June 4, 1973, Ser. No. 366,567

Claims priority, application Great Britain Dec. 15, 1972

Term of patent 14 years

Int. Cl. D27—05

U.S. Cl. D27—36

FIG. 1.

FIG. 2.

FIG. 3.

FIG. 1 is a perspective view of a switch for table cigarette lighter showing my new design;

FIG. 2 is a side elevation thereof; and,

FIG. 3 is a rear elevation thereof.

The base of the lighter is shown in broken lines for illustrative purposes only.

I claim:

The ornamental design for a switch for table cigarette lighter, as shown and described.
